7 Claims

The present invention relates to a process for defouling process equipment. More particularly, the invention provides an effective method for defouling process equipment contaminated with combustible carbonaceous deposits.

The equipment utilized in many types of chemical processes becomes fouled from time to time by the formation of combustible carbonaceous contaminants. Exemplary of equipment susceptible to fouling by the formation of carbonaceous contaminants are thermal cracking units, hydrocracking units, polymerization units, etc. A number of procedures have heretofore been used to clean up fouled equipment. Thus, the carbonaceous materials may be burned with steam diluted with air or subjected to chemical washing. These procedures have not been entirely satisfactory or practical in many cases. For example, combustion of carbonaceous contaminants in hydrocracking units with steam diluted with air often requires unit shutdown times on the order of days or weeks. Extended shutdown periods of this order cannot, of course, be tolerated from an economic standpoint.

In accordance with my present invention, an improved process is provided for defouling equipment of combustible carbonaceous contaminants. More particularly, the invention enables relatively rapid combustion of carbonaceous contaminants contained in process equipment. Various other objects and advantages of the invention will become apparent from the following detailed description thereof.

Briefly, the defouling process contemplated by the invention comprises contacting the fouled surfaces of the equipment with an admixture of an oxygen-containing gas and water at an elevated temperature and superatmospheric pressure sufficient to maintain at least a portion of the water in the liquid phase. Under these conditions, the carbonaceous deposits are rapidly combusted and the heat of combustion is absorbed by the liquid water. The absorption by the water of the heat given off in the combustion avoids excessive temperature increase, and accordingly renders the present invention practical in defouling equipment not capable of withstanding the relatively high temperature attendant prior art steam-air defouling operations.

As just noted, it is a prime requirement of the invention that the temperature and pressure conditions at which the contacting with the carbonaceous contaminants within the equipment to be defouled is carried out are such to maintain liquid phase water in contact with the fouled equipment. For this purpose, the temperature of the oxygen containing gas-water mixture introduced into the equipment to be defouled is such that upon combustion of the carbonaceous contaminants, the temperature is not increased to above about 700° F. (approximately the critical temperature of water) by absorption of the heat given off in the combustion reaction. It will, of course, be appreciated that the extent or rate of combustion will be primarily determined by the maximum temperature reached in the contacting operation. Thus, at contacting temperatures below about 400° F., excessively long periods of time are required for defouling the equipment. Accordingly, the contacting temperature may, with advantage, range from about 400° F. to about 700° F. with the range of 500° F. to about 650° F. being particularly

2

desirable. The pressure at which the defouling operation of the invention is carried out is high enough to maintain at least some liquid phase water in contact with the fouled equipment at the operating temperature. Advantageously, the pressure is maintained within the range of from about 300 p.s.i.g. to about 5,000 p.s.i.g. particularly from about 700 p.s.i.g. to about 4,000 p.s.i.g.

The oxygen-containing gas useful in the present process may be any gas containing molecular oxygen, such as oxygen itself, air or oxygen-enriched air. Air is preferred.

In carrying out the present process, I prefer to maintain substantially all of the fouled equipment in contact with a continuous phase of liquid water having the oxygen-containing gas dissolved or dispersed therein. The oxygen-containing gas may preferably be passed through the fouled equipment at rates which result in at least a 50 volume percent inventory of liquid water in the fouled equipment. For this purpose, the oxygen-containing gas may be passed through the equipment at rates ranging from about 0.03 to about 0.5 ft.³/sec. per square foot of equipment cross-section, preferably from about 0.05 to about 0.3 ft.³/sec. per ft.² of cross-section.

Various suitable methods may be employed for maintaining the fouled equipment in substantially complete contact with a continuous phase of liquid water with the oxygen-containing gas dissolved or dispersed therein during combustion of the carbonaceous deposits, in accordance with the preferred embodiment of the invention. By way of illustration, one suitable process scheme which may be employed is diagrammatically represented in the attached drawing.

Referring to the drawing, reference numeral 1 represents equipment to be defouled of combustible carbonaceous solids. Equipment 1 may, for example, be a reactor or ancillary apparatus employed in hydrocracking, thermal cracking, polymerization or like high pressure processes, which becomes fouled from time to time by the formation of combustible carbonaceous byproducts. When the buildup of carbonaceous solids seriously hampers the operation of the process, the supply of feed to the equipment is terminated and the equipment is then generally purged of residual liquid or vaporous material.

Defouling of equipment 1 is accomplished in accordance with a preferred embodiment of the present invention by introducing water having an oxygen-containing gas, such as air, substantially completely dissolved therein through inlet 2. The solution of oxygen-containing gas in water passed through the equipment under suitable conditions of pressure and temperature, as noted above, to maintain the water substantially solely in the liquid phase in contact with the fouled equipment, and to combust the carbonaceous contaminants.

The oxygen-lean solution is passed from the equipment 1 through line 3 and is introduced into an absorption tower 4. Air is supplied to the absorption tower 4 through line 5 and compressor 6 and is absorbed in the oxygen-lean water. Absorption efficiency is enhanced by allowing the water to descend through packing bodies 7 supported on a grid 8. The packing bodies are those conventionally used in absorbing towers, including Raschig rings, Berl saddles and the like. Gaseous products of the combustion of the carbonaceous contaminants, e.g., CO and CO₂, are partially stripped from the water, and along with steam and any excess oxygen-containing gas are vented from the absorbing tower through line 9. The water level in the absorbing tower may be maintained as desired by liquid level controller 10 which controls the operation of valve 11 in excess water drawoff line 12.

In order to maintain suitable pressure conditions for the defouling of equipment 1, absorber 4 is suitably maintained under a total pressure of from about 300 to about 5,000 p.s.i.g. and preferably 700 to 4,000 p.s.i.g., the oxy-

gen partial pressure being at least about 10 p.s.i., preferably 100 to 500 p.s.i. Furthermore, the temperature within the absorber 4 is preferably such that the vapor pressure of water is less than about 80% of the operating pressure. This practice minimizes the venting of large quantities of steam from the absorber through line 9.

The oxygen-rich water is passed from the absorption tower through line 13 and mixed in line 2 with make-up water charged through line 14. The amount and temperature of makeup water added through line 14 are such that there is no substantial vapor buildup in equipment 1 due to gassing off as the temperature is increased by the heat of combustion. As previously noted, by maintaining the air-water solution substantially solely in the liquid phase, possible dangers of explosion or damage to equipment 1 due to extremely rapid combustion occurring in vapor buildup areas are eliminated.

The time required for defouling the equipment is, of course, a function of the amount of carbonaceous contaminants contained therein as well as the temperature, total pressure and partial pressure and oxygen concentration, and may be readily determined by those skilled in the art as noted above. Compared to prior art processes employing steam diluted with air, defouling may be accomplished far more readily in accordance with the present invention.

The following specific examples are included for the purpose of further illustrating the invention, but are not intended to limit the invention thereto.

EXAMPLE 1

Using the procedure and apparatus arrangement described in reference to the drawing, a hydrogenation unit containing an estimated 800 pounds of combustible carbonaceous contaminants is defouled. Air, at the rate of 60,750 s.c.f.h. is added to an absorption tower, and therein is absorbed in oxygen-lean water passed from the hydrogenation unit being defouled. The absorption tower is operated at a temperature of 600° F. and a pressure of 3,000 p.s.i.g., which are essentially the temperature and pressure conditions at which the defouling of the hydrogenation unit is conducted. Oxygen partial pressure is approximately 310 p.s.i.

Water having air dissolved therein in the amount of 0.01 mole of O₂ per gallon of water, is passed from the bottom of the absorption tower at a rate of 18,700 gallons per hour and is combined with 246° F. make-up water added at the rate of 17,000 pounds per hour. The resultant admixture, which has a temperature of 581° F., is passed to the hydrogenation unit.

This procedure is continued for four (4) hours at which time the hydrogenation unit is ascertained to be completely defouled.

EXAMPLE 2

This example illustrates the use of the present invention in defouling a hydrocracking unit comprising a coil in which oil and hydrogen are reacted at high temperature and pressure. Coke and high molecular weight carbonaceous contaminants periodically buildup in the coil, thereby hampering efficient operation of the hydrocracking process. Heretofore, normal defouling procedure involved passing steam diluted with air through the coil. It was necessary to maintain the air concentration at a low level in order to prevent overheating and coil damage. However, on occasion, the coil was damaged by the excessive temperature attendant this type of defouling operation, requiring replacement of at least one coil section. Furthermore, down-stream equipment such as heat exchangers and the like could not withstand the high temperatures required for combustion on the carbonaceous contaminants (over 1,000° F.). Consequently, the down-stream equipment had to be dismantled and manually cleaned at considerable time and expense. The whole

operation required a minimum of four (4) to five (5) days and often much longer.

In accordance with the present invention, the following defouling operation is completed in twelve (12) hours without dismantling or damaging the equipment:

The hydrocracking operation is discontinued and the unit is cooled from operating temperature of 850° F. to about 600° F. During the cooling period, the normal heavy oil feedstock is discontinued in favor of a lighter, more volatile oil. After a two (2) hour wash with this oil, the oil feed is discontinued. Circulation of hydrogen at 600° F. vaporizes the oil in two (2) additional hours. The unit is then depressured and purged with flue gas, this operation requiring one (1) hour.

The defouling operation is conducted by maintaining the hydrocracking coil substantially completely in contact with a continuous phase liquid water having air dispersed therein. More particularly, water at the rate of 20,000 pounds per hour and air at the rate of 60,250 s.c.f.h. are continuously admixed and pumped through the coil. The temperature at the inlet is 524° F., while the temperature at the outlet is 26° higher (i.e. 550° F.) due to the heat given off by combustion of the carbonaceous deposits. Total operating pressure is 1500 p.s.i.g., and oxygen partial pressure is 95 p.s.i. After an operating period of about three (3) hours, the reaction temperature falls off to the inlet condition of 524° F., indicating that the bulk of the carbonaceous deposits has been combusted. The defouling operation is terminated after one (1) hour of operation, and the unit is then purged with flue gas for one (1) hour.

Hydrogen and oil feed to the unit are then resumed, and within two (2) hours the unit is again on-stream. The hydrocracking operation proceeds smoothly indicating that the carbonaceous contaminants are substantially completely combusted.

While the invention has been described above in connection with certain preferred embodiments thereof, it will be understood by those skilled in the art that various changes and modifications may be made without departing from the spirit and scope of the invention as expressed in the appended claims.

Therefore, I claim:

1. Process for defouling process equipment of combustible carbonaceous deposits which comprises contacting the surfaces of the process equipment fouled with carbonaceous deposits with an admixture of water and an oxygen-containing gas at an elevated temperature to combust the carbonaceous deposits and at a superatmospheric pressure sufficient to maintain the fouled surfaces of the equipment in substantially complete contact with a continuous phase of liquid water with the oxygen-containing gas dispersed therein during combustion of the carbonaceous deposits, the heat of combustion being at least partially absorbed by the liquid water.

2. Process as in claim 1 wherein the oxygen-containing gas and water are contacted with said fouled surfaces at a temperature of from about 400° F. to about 700° F. and a pressure of from about 300 p.s.i.g. to about 5,000 p.s.i.g.

3. Process as in claim 2 wherein the temperature is within the range of from about 500° F. to about 650° F. and the pressure is within the range of from about 700 p.s.i.g. to about 4,000 p.s.i.g.

4. Process as in claim 1 wherein substantially all of the surfaces of the fouled equipment are maintained in contact with a continuous phase of water in admixture with oxygen-containing gas.

5. Process as in claim 4 wherein the oxygen-containing gas is continuously passed through the fouled equipment at a rate which results in at least a 50 volume percent inventory of liquid water in the fouled equipment.

6. Process as in claim 1 wherein the oxygen-containing gas is substantially completely dissolved in the water and wherein the continuous phase of liquid water occupies substantially the entire volume of the fouled equipment.

7. Process as in claim 1 wherein the oxygen-containing gas is air.
